UNITED STATES PATENT OFFICE

2,478,592

LADDER

Curt E. Nyberg, Chicago, Ill., assignor, by mesne assignments, to Imagineering Corporation, Chicago, Ill., a corporation of Illinois

Application May 5, 1945, Serial No. 592,108

1 Claim. (Cl. 228—17)

1

This invention relates to ladders and more particularly to stepladders formed of sheet metal or like sheet material.

One of the objects of the invention is to provide a ladder which can be formed of sheet metal or the like and which provides maximum strength and rigidity with minimum weight.

Another object is to provide a ladder which can be easily and quickly assembled and disassembled. With this construction, the ladder can be shipped and sold in a knocked-down condition and can easily and quickly be put together by the purchaser.

In a preferred construction, the ladder is formed with a pair of side rails and a single back upright member which may be connected to a base member, formed for two point engagement with the ground.

Still another object is to provide a ladder which is automatically latched in open position when it is opened. The latching is preferably accomplished by a pivoted shelf which automatically moves to a horizontal position when the ladder is opened to hold the upright member in the desired relationship with the rails.

A further object is to provide a ladder in which steps are detachably secured to the side rails for easy assembly and disassembly. According to one feature, mounting means are provided which hold the steps on the rails and in addition detachable fastenings may be employed to secure the steps in place.

The above and other objects and advantages will be more readily apparent from the following description when read in connection with the accompanying drawing, in which—

Figure 1 is a perspective view of a ladder embodying the invention;

Figure 2 is a partial perspective illustrating an alternative method of connecting the upright to the side rails;

Figure 3 is an enlarged partial section of the top part of the ladder;

Figure 4 is a view similar to Figure 3 with the ladder in folded position;

Figure 5 is a section on the line 5—5 of Figure 3;

Figure 6 is an end view of the structure shown in Fig. 5, this structure being shown in a position in which the shelf 14 extends in a vertical plane;

Figure 7 is a partial perspective view of a step;

Figure 8 is an exploded perspective illustrating the step and a mounting means therefor;

Figure 9 is a perspective view of an alternative mounting bracket;

Figure 10 is an exploded perspective of a step and an alternative form of mounting bracket; and

Figure 11 is a perspective view illustrating an alternative step mounting construction.

The ladder, as illustrated in Figure 1, comprises

2

a pair of side rails 10, a back upright 11 pivoted between the side rails at the top of the ladder, a base member 12 supporting the upright, a plurality of steps 13 extending between the side rails and pivoted shelf 14. The side rails are preferably formed of sheet metal strips rolled at their edges as indicated at 15 to provide reinforcing and gripping flanges and which may be punched out as shown at 16 between the flanges to reduce the weight. The steps 13 are similarly formed of sheet metal strips rolled downwardly at their edges to provide reinforcing flanges. The central portions of the steps may be perforated to reduce weight or may be roughened if desired to prevent slipping. The upright 11 is a single metal tube or pipe pivoted at its upper end to a bracket 17 secured to the lower surface of the top step. The base member 12 is similarly formed of a metal tube bent into a U-shape and secured at its center to the lower end of the upright to support it.

Instead of securing the upright to a bracket such as 17 connected to the topmost step, the upper end of the upright may be connected through a T connector to a cross tube or pipe 18 whose ends are received in sockets 19 carried by the side rails. Otherwise the construction of Figure 2 is substantially identical to that of Figure 1 and may be assembled and used in the same manner.

The shelf 14 is formed with a pair of bars or rails 21 formed of metal strips or the like connected at their outer ends by a cross-piece 22 which may be integral with the bars or rails. A shelf member 23 of sheet metal or the like is fastened to the bars at their outer ends and is adapted to lie in a horizontal position when the ladder is opened. The bars 21 are pivoted at 24 to extensions on a bracket 25 which is secured to the bottom of a step 13 adjacent the top of the ladder. The bracket, as best seen in Figures 5 and 6, is formed with spaced sides between which the bars 21 move. At their inner ends, the bars carry a head member 26 adapted to fit relatively tightly between the sides of the bracket so that when the ladder is opened the head member will engage the sides of the bracket to brace the bars against lateral movement.

A ring 27 is pivoted between the bars 21 adjacent the shelf plate 23 and slidably encircles the upright 11. As the upright is swung out the ring 27 will slide down it until the shelf reaches a horizontal position with the head 26 fitting into the bracket 25. This prevents further downward movement of the shelf so that the ring 27 will hold the upright 11 in extended position as shown in Figures 1 and 3. When the ladder is folded for storage, the ring will slide up the upright 11 to the position shown in Figure 4 in which the upright and the shelf both lie sub-

stantially parallel to and closely adjacent the side rails so that the ladder occupies a minimum of space.

The steps 13 are detachably secured to the side rails and for this purpose are formed as shown in Figures 7 with end flanges 28 integral with the steps. Side flanges 29 integral with the end flanges 28 may be folded inwardly to underlie the central body portion of the steps and may be secured to the steps by fingers projecting through openings in the steps and peened over at the top of the steps. The side flanges 29 are preferably triangular, as shown, so that they taper downwardly. If desired, the steps and the end flange may be formed with one or more stiffening and reinforcing channels 31.

To secure the steps to the side rails, mounting brackets as indicated in Figure 8 are provided. As shown, the mounting brackets are formed of sheet metal having a top cross portion 32 with downwardly turned triangular side portions 33 which are folded back upon themselves as shown at 34 to form downwardly tapering pockets. The side flanges 34 are formed with projecting lugs or fingers 35 to extend through openings in the side rails and which may be peened over to secure the brackets in place. In addition, the brackets may be spot-welded to the side rails at one or more points, if desired.

With the several mounting brackets secured to the side rails, the top cross portions 32 and the edges of the end flanges 33 will lie spaced from the inner surface of the side rails. The step may then be placed in position on the bracket with the end flange 28 passing between the top portion 32 and the side rail and with the triangular flanges 29 fitting into the correspondingly shaped pockets formed by the flange portions 33 and 34 of the brackets. It will be seen that this construction adequately supports the steps without any additional fastenings but it is preferred that a bolt or like detachable fastening be inserted through openings 36 in the steps and the top portions 32 of the brackets to make the construction more rigid and to prevent accidental displacement of the steps.

Figure 9 illustrates an alternative bracket construction which may be used in place of the bracket of Figure 8. In this construction, the bracket is formed of sheet metal having a cross portion 37 adapted to lie parallel to and spaced from the side rails. Triangular end flange portions 38 are bent outwardly from the ends of the cross portion 37 and are bent back upon themselves at 39 to form downwardly tapering pockets to receive the side flanges 29 on the steps. The flange portions 39 may be secured to the side rails by projecting fingers or lugs thereon and in addition by spot-welding at one or more points, if desired. The steps may be assembled on the brackets of Figure 9 in much the same manner as on the brackets of Figure 8 and may be held thereon by bolts or like detachable fastenings extending through holes 41 in the cross members 37 and through complementary holes in the side rails.

Figure 10 illustrates another mounting construction for the steps in which the ends of the steps are cut off straight and are drilled as indicated at 42. As shown in this figure, the steps may be formed with a series of perforations 43 to reduce their weight and to provide a rough tread portion. Mounting brackets in the form of metal stampings 44 are provided having flat upper plate portions 45 to underlie the end por-

tions of the steps and downwardly extending flange portions 46 to lie against the side rails. The portions 45 and 46 are connected by integral web portions 47 to reinforce and strengthen the brackets. The flange portions 46 of the brackets are formed with openings 48. Bolts may be extended through openings 48 and aligned openings in the side rails to secure the members 44 upon the side rails. In addition one or more spot-welds may be used to form a rigid permanent connection between the brackets and the side rails.

In assembling the steps on these brackets, the end portions of the steps are laid over the brackets with the rolled edges thereof overlying the sides of the brackets. The top plate portions 45 are formed with holes 49 to register with the holes 42 in the steps so that bolts or like detachable fastenings can easily be inserted to secure the steps to the brackets.

Still another fastening construction is shown in Figure 11 in which the side rails 10 carry a series of headed rivets 51 to fit into key hole slots 52 formed in an end flange on the steps 13. The holes 52 may be formed in a flange similar to the flange 28 of Figure 7 and are spaced to fit over the rivets 51 to secure the steps to the side rails. In addition bolts or the like may be inserted through holes 53 in the step flanges and in the side rails to prevent accidental removal of the steps.

With the construction of this invention, the ladders may be shipped in a knocked-down condition and may be easily assembled by the purchaser. To assemble the ladders, it is necessary only to attach the steps to the mounting brackets which are permanently assembled on the side rails to insert the uprights 11 through the ring 27 and pivotally connect it to its bracket 17. The shelf bracket 25 will be installed at the factory by riveting or the like to the proper one of the steps and the supporting bars 21 of the shelf will be pivotally connected to the brackets by rivets or the like. Therefore, when the steps are assembled to the side rails the shelf will be properly positioned so that it is only necessary to insert the upright through the ring 27 and to pivotally connect it to the bracket 17 to complete the assembly. In the construction of Figure 2, the assembly may be performed in the same manner except that the upright is connected to the T member in the cross-rod 18 rather than to the bracket.

When so assembled, the ladder can easily be used simply by swinging the upright away from the side rails to extend the ladder. As explained above, the shelf will automatically swing down during this operation to lock the ladder in extended position.

While several embodiments of the invention have been shown and described in detail, it will be understood that they are illustrative only and are not to be taken as a definition of the scope of the invention, reference being had for this purpose to the appended claim.

What is claimed is:

A ladder comprising a pair of side rails, a plurality of cross members connecting the side rails and forming steps, a single upright member pivotally connected between the side rails adjacent the top of the ladder to swing toward and away from the plane of the side rails, a bracket on one of the cross members, a shelf member pivoted at one end to the bracket, means slidably connecting the shelf member to the upright, and interengag-

ing parts on the bracket and the shelf member to brace the shelf member when it is in a horizontal position.
